UNITED STATES PATENT OFFICE.

IVAN O. GARDNER, OF SOMERSET, PENNSYLVANIA, ASSIGNOR OF ONE-HALF TO
GEORGE H. EMERSON, OF BALTIMORE, MARYLAND.

LATERALLY-ADJUSTABLE DRIVING BOX.

Application filed June 6, 1925. Serial No. 35,396.

To all whom it may concern:

Be it known that I, IVAN O. GARDNER, a citizen of the United States, residing at Somerset, in the county of Somerset and State of Pennsylvania, have invented certain new and useful Improvements in Laterally-Adjustable Driving Boxes; and I do hereby declare the following to be a full, clear, and exact description of the invention, such as will enable others skilled in the art to which it appertains to make and use the same.

My invention relates to laterally adjustable driving boxes.

The primary object of my invention is to devise a driving box so constructed and arranged that the same may be laterally adjusted without removal from under the locomotive.

A further object is to devise a box of the character described which requires a minimum of change in present standard and working equipment and which is also characterized by an ability to compensate for the wear in the pedestal shoe and wedge.

The clearance between the driving wheel hub and box, known as the "lateral," must, under present rulings of the Interstate Commerce Commission, be kept within certain definite limits. At this point of the locomotive, however, due to the frictional contact of the box with the wheel hub, the rate of wear is relatively high and particularly so with locomotives having comparatively long and rigid wheel bases.

Many methods have been devised heretofore for maintaining this lateral clearance, notably the provision of refacing the driving box with a wear plate of proper design. This solution is objectionable in that it is necessary to remove the locomotive from service for a considerable time. Other methods have overcome the latter objection by providing a means for adjusting for the lateral play without removing the wheels or boxes from the locomotive, but as they require extensive changes in standard equipment for their installation, the same have not been generally adopted.

I have devised a means for taking up the excess lateral clearance, as will become more apparent hereinafter, my invention being characterized by extreme simplicity and low cost of installation. No additional elements, beyond those now utilized in boxes of ordi-

nary construction, are required, other than easily removable wear plates, and a slight change only is made necessary in the present standard box.

These and further objects will be set forth in the following specification, reference being had to the accompanying drawings, and the novel means by which said objects are effectuated will be definitely pointed out in the claims.

In the drawing:

Fig. 1 is a sectional elevation of my improved driving box, showing the same mounted in a frame.

Fig. 2 is a section along the line 2—2 70 in Fig. 1, looking in the direction of the arrows.

The numeral 5 represents the frame of a locomotive provided with a pedestal composed of the sides 6—6 which are united at their bottoms by the pedestal brace 7. A pedestal shoe 8 and a pedestal wedge 9 embrace the sides 6—6 in the usual manner and the latter is provided with the customary inclined surface for coacting with a similarly inclined surface formed on one of the sides 6. The driving box 10 is slidably mounted between the shoe 8 and wedge 9 and proper engagement of said wedge with said box is obtained by means of the wedge bolt 11 which extends through the brace 7, the upper end of said bolt being operatively connected to said wedge in any approved manner in order to achieve this result. An axle 12 is journaled in the box 10 and a wheel 13 is secured to each end thereof with the proper lateral clearance from the outer face of each of said boxes. For purposes of illustration, one box and wheel only are shown in Fig. 2.

The driving box is, generally considered, formed in the usual manner, but is specifically constructed to be adapted for transverse movement relative to the shoe 8 and wedge 9, and therefore to the frame 5. This condition is obtained by forming a plurality of recesses 14 in the box 10, one recess being disposed adjacent each outer corner of said box. One wall of each recess is formed by a continuation of the face of the box which contacts with the shoe and wedge and the opposite wall thereof forms the shoulder 15, the distance between shoulders on the same side of the box being greater than the depth of the shoe, or the wedge. It is ob-

vious that, due to the latter provision, the box 10 may be laterally shifted along the axle 12 until the proper clearance is established between the outer face of the box 10 and the hub of the wheel 13.

In order to position the box 10 in any desired location, I employ the wear plates 16 which, when the box is first adjusted, are preferably of different thicknesses, the thin plates being positioned on that side of the box adjacent the wheel 13 and the thicker plates on the opposite side of said box. Said plates rest on shoulders 17 which form the bottoms of the recesses 14 and are prevented from endwise movement in the opposite direction by screws 18. The foregoing manner of securing the plates 16 is intended merely for purposes of illustration as it is apparent that other means may be employed without violating the spirit of my invention. In order to facilitate withdrawal of the plates from the recesses, the latter preferably extend above the top of the box as shown in Fig. 1.

When the clearance between the box 10 and the hub of the wheel 13 becomes greater than is allowed by law, or is undesirable for other reasons, the box may be shifted laterally a suitable distance by transposing the thin plates to the opposite side of the box and by performing a similar step with the thick plates. The box 10 will then have been shifted a distance equal to the difference between the thicknesses of the plates. It is obvious that many locations of the box 10 may be obtained by properly selecting wear plates of varying thicknesses, or the same result may be achieved by forming said plates in the shape of wedges. Further, the plates may be disposed initially only on one side of the box and afterwards transposed and other combinations will occur to one skilled in the art.

From the foregoing, it is apparent that I have provided a means for taking up the lateral clearance which is characterized by simplicity, rapidity and low cost of installation. No changes are required in present standard equipment, other than the recesses in the box, to which reference has been made. Moreover, it is obvious that, by positioning the wear plates between the box and the shoe and wedge, respectively, adjustment is also provided for wear on the sides of the latter elements.

While I have shown one set of elements and combinations thereof for effectuating my improved driving box, it is to be understood that the same is for the purposes of illustration only and in no wise to limit the scope of my invention, for many changes may be made in the structure shown and described without departing from the spirit of my invention.

I claim:—

1. The combination with a frame, of wear members mounted therein, a driving box slidably mounted in said members and means insertible between said box and members for shifting said box transversely to said frame.

2. The combination with a frame, of wear members mounted therein, a driving box slidably mounted in said members and means engaging between one side of said members and said box and transposable for engagement between the opposite side of said members and said box for shifting the latter transversely to said frame.

3. The combination with a frame, of wear members mounted therein, a driving box slidably mounted in said members, means engaging between one side of said members and said box and transposable for engagement between the opposite side of said members and said box for shifting said box transversely to said frame and means for securing said first named means in position.

4. The combination with a frame, of wear members mounted therein, a driving box mounted in said members, and means engaging between the sides of said members and said box and transposable for engagement between the opposite sides of said members and said box for shifting said box transversely to said frame.

5. The combination with a frame, of wear members mounted therein, a driving box mounted in said members, means engaging between the sides of said members and said box and transposable for engagement between the opposite sides of said members and said box, and means for securing said first named means in position.

6. The combination with a frame, of channel members disposed to embrace said frame, a driving box mounted in said members and means insertible between said members and said box for shifting said box transversely to said frame.

7. The combination with a frame of channel members disposed to embrace said frame, a driving box mounted in said members and means engaging between one side of said members and said box and transposable for engagement between the opposite side of said members and said box for shifting the latter transversely to said frame.

8. The combination with a frame, of wear members mounted therein, a driving box mounted in said members and means carried by said box for shifting the same transversely to said frame.

9. The combination with a frame, of wear members mounted therein, a driving box mounted in said members and means, carried by said box, engaging between one side of said members and said box and transposable for engagement between the opposite

side of said members and said box for shifting the latter transversely to said frame.

10. The combination with a frame, of wear members mounted therein, a driving box mounted in said members and means, carried by said box, engaging between the sides of said members and said box and transposable for engagement between the opposite sides of said members and said box for shifting the latter transversely to said frame.

11. The combination with a frame, of channel members disposed to embrace said frame, a driving box mounted in said members and adjusting plates insertible between said members and box for shifting the latter transversely to said frame.

12. The combination with a frame, of channel members disposed to embrace said frame, a driving box mounted in said members and adjusting plates, carried by said box, insertible between said members and box for shifting the latter transversely to said frame.

13. The combination with a frame, of wear members mounted therein, a driving box mounted in said members and adapted for transverse movement relative thereto, and means engaging between said members and box for maintaining the latter in a plurality of laterally shifted positions.

14. The combination with a frame, of wear members mounted therein, a driving box mounted in said members and adapted for transverse movement relative thereto, and means, carried by said box, engaging between said members and box for maintaining the latter in a plurality of laterally shifted positions.

15. The combination with a frame, of wear members mounted therein, a driving box mounted in said members, an axle journaled in said box and provided with a wheel spaced from said box, and means interposed between said members and box for shifting the latter toward said wheel.

16. The combination with a frame, of

wear members mounted therein, a driving box mounted in said members and laterally shiftable relative thereto, an axle journaled in said box and provided with a wheel spaced from said box, and means engaging between said members and box for maintaining the latter in a plurality of laterally shifted positions.

17. The combination with a frame, of wear members mounted therein, a driving box slidably mounted in said members, and means for compensating for the wear on the sides of said members.

18. The combination with a frame, of wear members mounted therein, a driving box slidably mounted in said members, and means carried by said box for compensating for the wear on the sides of said members.

19. The combination with a frame, of wear members mounted therein, a driving box slidably mounted in said members, and selectively adjustable means for compensating for the wear on the sides of said members.

20. The combination with a frame, of wear members mounted therein, a driving box slidably mounted in said members, and selectively adjustable means carried by said box for compensating for the wear on the sides of said members.

21. The combination with a frame, of channel members disposed to embrace said frame, a driving box mounted in said members and independently adjustable plates insertible between said members and box for shifting the latter transversely to said frame.

22. The combination with a frame, of wear members mounted therein, a driving box slidably mounted in said members and independently adjustable means insertible between said box and members for shifting said box transversely to said frame.

In testimony whereof, I affix my signature.

IVAN O. GARDNER.
